(57) **CLAIM**

The ornamental design for a jacket with removable and integrated backpacks, as shown and described.

DESCRIPTION

FIG. 1 is a right-side perspective view of a jacket with multiple integrated backpacks, showing my new design with an outer backpack in a collapsed configuration; FIG. 2 is a front elevational view of FIG. 1; FIG. 3 is a rear elevational view of FIG. 1; FIG. 4 is a left-side elevational view of FIG. 1; FIG. 5 is a top plan view of FIG. 1; FIG. 6 is a bottom plan view of FIG. 1; FIG. 7 is a front perspective view thereof; FIG. 8 is a front perspective view thereof; FIG. 9 is an exploded right-side elevational view thereof, illustrated with the first backpack in an expanded configuration with arm straps uncompressed, the first backpack unzipped from and exploded away from a second backpack that is also in an expanded configuration; FIG. 10 is an exploded front perspective view thereof; FIG. 11 is an exploded rear elevational view of FIG. 9, illustrated with the first backpack to the side of the jacket for clarity of illustration; FIG. 12 is an exploded top plan view of FIG. 9; FIG. 13 is an exploded bottom plan view of FIG. 9; FIG. 14 is a rear perspective view of FIG. 9 but with the first backpack omitted for clarity of illustration; FIG. 15 is a rear elevational view of FIG. 14; FIG. 16 is a top plan view of FIG. 14; and, FIG. 17 is a bottom plan view of FIG. 14. The broken lines showing a person in FIG. 1 depict environmental matter and form no part of the claimed design. The remaining broken lines represent stitching, and are part of the claimed design.

1 Claim, 10 Drawing Sheets
